UNITED STATES PATENT OFFICE.

HENRY SMITH, OF RICHMOND, VIRGINIA, ASSIGNOR TO STANDARD CHECK BOOK COMPANY, INCORPORATED, OF RICHMOND, VIRGINIA, A CORPORATION OF VIRGINIA.

CHECK-BOOK.

1,307,708.

Specification of Letters Patent. Patented June 24, 1919.

Application filed April 4, 1917. Serial No. 159,690.

To all whom it may concern:

Be it known that I, HENRY SMITH, a citizen of the United States, residing at Richmond, in the county of Henrico and State 5 of Virginia, have invented a new and useful Check-Book, of which the following is a specification.

The present invention appertains to check books, and aims to provide a check book 10 wherein the back, checks, stubs and cover are assembled in a novel manner, in order that the stubs can be readily filled in and the checks easily detached, the present check book being thoroughly practical and convenient in use.

With the foregoing and other objects in view which will appear as the description proceeds, the invention resides in the combination and arrangement of parts and in the 20 details of construction hereinafter described and claimed, it being understood that changes in the precise embodiment of the invention herein disclosed can be made within the scope of what is claimed without deviating from the spirit of the invention.

The invention is illustrated in the accompanying drawing, wherein:—

Figure 1 is a perspective view of the improved check book, with the cover swung 20 open, the stubs turned up, and some of the checks removed, part of the cover being broken away.

Fig. 2 is a sectional detail taken on the line 2—2 of Fig. 1, with all of the stubs turned down.

Fig. 3 is a view similar to Fig. 1 illustrating a modification.

The book comprises a rectangular back 1 of cardboard or other relatively stiff material, and a cover 2 of the same shape and preferably of the same material. One end of the cover 2 is connected by a flexible hinge web 2' with one end of the back 1, whereby the cover can be swung open toward the left side, the cover being hinged to the left hand end of the back 1. Disposed upon the back 1 are superposed sheets 3 of paper or other suitable material, each of which has printed thereon a plurality of blank checks 4 and stubs at the left hand ends of the checks. As illustrated, there are three checks for each sheet disposed longitudinally and parallel with one another and having their left hand ends united with the stubs. The checks 4 are rendered detachable from the stubs by lines of perforations 6 between them and extending from the upper to the lower edges of the sheets 3, and the checks are rendered detachable from one another by longitudinal lines of perforations 7 between them and extending from the line of perforations 6 to the right hand ends of the sheets 3. The stubs 5 of each sheet are united in column formation and are not detachable from one another.

To secure the sheets 3 in place, the upper ends of the sets of stubs 5 are secured, as at 8, by means of staples or other suitable fastening means upon the back 1 adjacent to the upper edge and left hand end thereof. This is the only point at which the sheets are attached to the back. A binding 9 is also preferably cemented or pasted around the upper ends of the stubs, the edges of the binding being pasted upon the stubs and under the back 1, respectively, as seen by reference to Fig. 2. The checks are free and are only held in place by their attachment to the stubs, and the checks can be readily detached from the stubs as the checks are used. The stubs of the detached checks can be turned up out of the way, as illustrated in Fig. 1, being swung upwardly over the upper edge of the back 1. In this manner, the filled in stubs will not interfere with the filling in of the successive stub as the checks are used, the cover 2 being swung open conveniently toward the left out of the way, thus enabling the stubs to be swung upwardly. This provides a convenient and practical arrangement. Should it be desired to keep the place marked where the stubs are being filled in, the cover 2 can be swung over the sheets 3 with the used stubs turned up, as seen in Fig. 1, thereby holding the turned-up stubs in place, and covering the checks and stubs which are being used or which are to be filled in. It is therefore advantageous to hinge the cover to that end of the back 1 adjacent which the stubs are located, the stubs swinging upwardly while the cover swings open to the left. Furthermore, since all of the stubs will remain intact, when the cover is swung over the stubs with all of the stubs turned down, the thickness of the check book at the hinge will always remain the same, while the free end of the cover can be brought closer to the right.

hand end of the back 1 as the checks are removed. This prevents a distortion of the hinge.

With the present device, each of the stubs 5 is provided along the right hand edge with a column 10 having the heading "checks" 10' at the upper end thereof, in which the amount of the respective checks can be written. Each set of stubs is also provided 10 along the left hand end edge thereof with a column 11 having the heading "deposits" 11', in order that the deposits can be entered in the column 11. Balances can be taken from 15 time to time, as indicated in Fig. 1, and since both columns 10 and 11 are readily accessible, this provides a complete and satisfactory arrangement.

It is also preferable to rule the under sides 20 of the stubs 5, as at 12, whereby when the stubs are turned up, memoranda may be written thereon, the under surface of each set of stubs being provided with a suitable heading 13 if desired.

The structure shown in Fig. 3 is similar 25 to that shown in Fig. 1, and in addition the sheets 3 are provided at their left hand ends with transverse strips 14 at those edges of the stubs 5 opposite to the checks 4. The stubs 5 are rendered detachable from the 30 strips 14 by transverse lines of perforations 15 between the strips 14 and stubs 5 and par-

allel with the lines of perforations 6. The web 2^a between the back 1 and cover 2 extends around the strips 14 and provides a binding uniting said strips and the corresponding ends of the sheets 3. This holds the left hand ends of the sheets firmly in place, but as the checks are removed, the stubs 5 can be torn loose from the strips 14, as seen in Fig. 3, but the web 2^a and cover 2 40 are still firmly connected with the strips 14 and back 1.

Having thus described the invention, what is claimed as new is:—

A check book comprising a back, a pad 45 of sheets mounted on the back, each sheet perforated to form a stub and a check, said stubs secured together and to the back along their upper edges, a cover, and a flexible web secured to the respective ends of the back 50 and the cover to form a hinge whereby the cover may be folded over upon the pad and may be swung free of the stubs to allow the stubs to be folded upwardly for easy inspection of the stubs. 55

In testimony that I claim the foregoing as my own, I have hereto affixed my signature in the presence of two witnesses,

HENRY SMITH.
